UNITED STATES PATENT OFFICE.

LUCIAN E. PARKER, OF WADSWORTH, OHIO, ASSIGNOR TO THE OHIO MATCH COMPANY, OF WADSWORTH, OHIO, A CORPORATION OF OHIO.

LINK CARRIER FOR PAPER-MATCH MACHINES.

Application filed December 1, 1924. Serial No. 753,409.

To all whom it may concern:

Be it known that I, LUCIAN E. PARKER, a citizen of the United States, residing at Wadsworth, in the county of Medina and 5 State of Ohio, have invented a certain new and useful Improvement in Link Carriers for Paper-Match Machines, of which the following is a full, clear, and exact description.

10 The object of this invention is to provide an improved form of link carrier for use in machines for making paper, strip or card matches, by which the match strip or card is securely held, without the intervention of 15 springs, while the strip is being carried through the machine for dipping and drying purposes.

The invention consists of a link having any desired number of transverse grooves, 20 in which grooves are staggered projections of substantially the depth of the grooves and extending from opposite side walls thereof in staggered relation, so that the flexible match strips or cards may be inserted by 25 hand or otherwise in these grooved links and held therein by deflection incident to contact with the staggered projections, but without permanently distorting the strips, as I will proceed now to explain and finally claim.

30 In the accompanying drawings illustrating the invention, in the several figures of which like parts are similarly designated, Figure 1 is a plan view of two connected links made in accordance with the present 35 invention. Fig. 2 is an end view of one of the links on a larger scale than Fig. 1, and showing in dotted lines match strips inserted in the links. Fig. 3 is a cross-section of one of the links. Fig. 4 is a top plan view 40 showing a part of the link with a part of a match strip or card inserted therein.

The body 1 of the link is made with the transverse grooves 2 having the projections 3 and 4 extending from the opposite side 45 walls of the grooves in staggered relation and of substantially the depth of the grooves, as shown more in detail in Fig. 3. These projections are shown as of curvilinear outline, and this conformation will be found 50 satisfactory, although the invention is not limited to the curvilinear projections. It is advisable, however, that these projections should not extend into the grooves from either side for a distance greater than half 55 of the width of the grooves.

The usual end elements 5 are formed on the links whereby a series of links may be connected in an endless carrier, which is suitably mounted and adapted to be moved from end to end of the machine for finishing the 60 matches, as usual. These end elements likewise have the teeth 6 for engaging sprocket wheels by which the carrier is supported and moved, as usual.

As indicated in Figs. 2 and 4, the match strips are inserted in the grooves and their uncut margins are engaged by the projections 3 and 4, which will put bights in the strips and thereby serve to hold the strips securely in the links without the intervention of springs or other yielding devices, such as have been commonly used heretofore.

The deflection of the uncut margin of the strips by reason of its engagement with the 75 projections 3 and 4 is only temporary, and when the strips are discharged or ejected from the links they will automatically resume their original flatness.

The bottoms of the grooves are provided 80 with the through holes 7 for receiving the ejector pins commonly used in this class of machines for discharging or ejecting the finished strips from the links.

It may be repeated, in another way, that 85 the projections 3 and 4 serve to very slightly deflect back and forth or crimp the match strip throughout its entire length, but not enough to distort the splints to be operated on or to permanently corrugate or crimp the 90 strips.

Variations in the details of construction and the shape of the projections are permissible within the principle of the invention as herein explained and hereinafter 95 claimed.

What I claim is:—

1. A link carrier for paper match machines, having transversely grooved links provided with projections from the side 100 walls of said grooves and extending into the grooves in staggered relation.

2. A link carrier for paper match machines, having links transversely grooved, each groove partly occupied by projections 105 extending from its opposite side walls in staggered relations and adapted to grip and hold the match strip or card while such strip or card is being carried through a match making machine.

3. A link carrier for paper match machines, having transversely grooved links, said grooves provided with curved projections extending into the grooves from opposite side walls thereof alternately and adapted to hold the match strips or cards while temporarily crimping them, and means

to permit the ejection or discharge of the strips.

In testimony whereof I have hereunto set my hand this 29th day of November A. D. 1924.

LUCIAN E. PARKER.
